UNITED STATES PATENT OFFICE.

WILLY HORNAUER, OF NEUKOLLN, GERMANY, ASSIGNOR TO TELEGRAPHIE-GESELLSCHAFT MIT BESCHRÄNKTER HAFTUNG SYSTEM STILLE, OF BERLIN, GERMANY.

CONTROLLING DEVICE FOR ELECTROMAGNETIC TALKING MACHINES.

Application filed June 20, 1925, Serial No. 38,556, and in Germany July 3, 1924.

This invention relates to an electro-magnetic talking-machine of the Poulsen type in which the record is impressed magnetically on a steel wire which is fed from one spool to another and which passes between the poles of magnets that either receive impulses from the wire and transform them by means of a diaphragm into sound waves or, conversely, record received sound waves magnetically on the wire, a driving motor being employed to which either spool can be coupled by means of a suitable clutch for taking up the wire.

The object of the present invention is to facilitate the control of the machine, and the invention consists in the provision of clutches whereby both spool spindles are normally coupled to the driving mechanism so as to maintain the record wire taut, each clutch being controlled by a lever which, when depressed for releasing the clutch and the spool spindle, at the same time operates two electric circuits, one for closing the magnet circuit and another for starting the driving mechanism.

Such a device is illustrated diagrammatically by way of example in the accompanying drawing in which the spools and their driving elements are shown in section.

The machine is fitted with two upright, rotatable spindles B and B' which are mounted in bearings C, D and C', D' respectively and adapted to receive for rotation the spools A and A' on which the record wire F is wound. The spindles are driven by means of an electro-motor S from which motion is transmitted to pulleys G and G' fitted loosely on the spindles. The pulleys are adjustable on the spindles so that they can be shifted in an axial direction into and out of engagement with friction discs L, L' which are fast on the spindles. For this purpose the pulleys are controlled by levers N and N' which are pivoted respectively at M and M' to the machine frame. In operation, one spindle is coupled to the driving mechanism in this manner for taking up the wire, the other spindle being disengaged for delivering the wire. Normally, both pulleys are held in engagement with their friction discs by springs Q and Q' which bear for this purpose against the free ends of the levers N, N'. Keys O, O' are fitted in the free ends of the levers so that they

can be used for depressing the latter and releasing the spindles when required. The lower ends of the keys are shouldered for engagement with pivoted catches R, R' adapted to retain the levers in operated position.

The magnets which cooperate with the record wire F in recording and reproducing the sound, are energized by a battery E, and contact springs V, W and V', W', whereby the circuit can be closed, are arranged under the keys O, O' so as to be actuated by the latter for closing the circuit. The circuit of the driving motor S is controlled by a similar set of contact springs T, U and T', U', and the springs T, T' are connected to the springs V, V' so that both circuits will be closed when one of the keys is depressed.

When the machine is at rest, both spools A, A' are coupled to the driving mechanism. To start the machine, the delivery spool must be released, and for this purpose the key appertaining to it must be depressed so as to occupy the position shown to the left in the drawing. The two switches will also be operated by the key so as to start the motor and so as to close the circuit of the magnet system E. As soon as the key is released from the catch R, the machine will be stopped and the magnet circuit broken while the driving pulley will be reengaged to its friction disc so as to keep the wire taut.

I claim:

1. An electro-magnetic talking-machine of the character described, comprising a magnet system, an electric circuit for said system, a record wire cooperating with said magnet system, spools carrying said wire, rotatable spindles carrying the spools, a driving mechanism for said spindles including a motor, clutch members whereby said spindles are normally coupled to the driving mechanism, clutch-controlling members, and means whereby either of said clutch controlling members, when actuated for releasing a spindle, causes the magnet circuit to be closed and the motor to be started.

2. An electro-magnetic talking machine of the character described, comprising a magnet system, an electric circuit for said magnet system, a record wire cooperating with

said magnet system, spools carrying said wire, spindles carrying the spools, clutch members secured to said spindles, driving pulleys arranged loosely on the spindles and 5 adapted to engage said clutch members for driving the spindles, spring-pressed levers holding the pulleys normally in engagement with the clutch members, keys for operating

said levers so as to release the pulleys, an electric driving motor, and switches arranged under said keys so as to be operated by the latter, when depressed for disengaging a pulley, for closing the magnet circuit and for starting the motor. 10

WILLY HORNAUER.
